UNITED STATES PATENT OFFICE.

JAMES W. LONEY AND THEODORE C. STEGER, OF FORT WAYNE, INDIANA.

WATER-GAGE SHIELD.

1,114,778.

Specification of Letters Patent.

Patented Oct. 27, 1914.

Application filed February 4, 1914. Serial No. 816,636.

To all whom it may concern:

Be it known that we, JAMES W. LONEY and THEODORE C. STEGER, citizens of the United States, residing at Fort Wayne, in 5 the county of Allen and State of Indiana, have jointly invented a new and useful Water-Gage Shield, of which the following is a specification.

Our invention relates to water gage shields intended to protect persons working 10 in close proximity to such gages in locomotives on stationary boilers from injury which might be caused by flying glass, steam and water, in the event of the bursting of 15 the gage glass tube.

It is an object of our invention to overcome this danger by providing a pipe for taking the steam and water out of range and further by providing a pressure tight shield.

20 It is also our object to provide a device that may be readily disassembled in the event of the water tube breaking or for other reasons when desired.

25 It is an object of our invention to combine with such a shield improved means for holding a lamp in a suitable position to reflect light on the gage and to provide a form of lamp bracket to which corresponding brackets on the lamp member may be readily 30 adjusted and secured.

35 It is also our object to provide a new combination and arrangement of parts, to provide a safer and more effective shield, and to improve various parts of the device as described and illustrated.

Referring to the drawings, Figure 1 is a front view of our invention in use; Fig. 2 is a side view of same; Fig. 3 is a horizontal section on line 3—3 of Fig. 2; Fig. 4 is a 40 perspective view of the band and lamp bracket; Fig. 5 is a vertical section on line 5—5 of Fig. 2; Fig. 6 is a horizontal section; Fig. 7 is a view partly in section, of a modified form of our invention; Fig. 8 is a 45 plan view of member 3^a.

In the accompanying drawings, 1 indicates our semicylindrical metal shield member, which may be made of aluminum, brass, or other suitable metal; and 2 indicates a 50 corresponding semicylindrical glass shield member, which may be of very heavy wire glass or plate glass, $\frac{3}{8}$ " to $\frac{1}{2}$ " in thickness. The longitudinal edges of metal shield member 1 are provided with grooves holding 55 rubber gaskets, indicated by 7, 7, against which the longitudinal edges of glass shield

member 2 are pressed. Adjustable shield bands 4, 4 having offset hinged portions, are disposed about the top and bottom portions of shield members 1 and 2 to secure them in place. Thumb screws 5, 5 in bands 4, 4 opposite to the offset hinged portions provide means for adjusting the bands 4, 4 to effect a steam and water tight joint under pressure.

The ends of shield members 1 and 2 are pressed against rubber end gaskets 8, 8, which in turn are supported by metal disks 18, 18, and outer adjustable flanged disks 3, 3, which screw up and down on threads on the gage cocks. The metal disks 18, 18, serve to prevent tearing of gaskets 8, 8 so that when adjustable flange disks 3, 3 are adjusted a steam and water tight joint is effected at the ends of the shield members 75 and the protection afforded by the shield is increased.

In metal shield member 1 we provide a discharge pipe 6 for conveying steam and water to ashpan or pit of boiler and to instantly release pressure in the shield in case of breakage of the gage.

In the drawings, it will be observed that gaskets 10, 10 are provided, disposed in interior grooves provided in bands 4, 4, as 85 illustrated, and which prevents the metal bands from contacting with the glass shield member and rendering it liable to breakage in consequence.

Adjustable flange disks 3, 3 are provided 90 with extension bands 14, 14 that extend into the ends of the shield and are of such size as to allow free adjustment of the packing nuts 15 to gage glass 16.

It is necessary that artificial means of 95 lighting the gage glass be provided for use at night, and that the light be so positioned as not to interfere with a view of the water tube. To accomplish this we provide lamp brackets 9, 9. Each has a vertical stem portion attached to its band 4, and each terminates in a horizontally disposed flaring flange portion, as illustrated. The last-named portions of brackets 9, 9, are each provided with spaced orifices in which lamp 105 bracket wires 17, 17, are mounted. Their function is to secure a suitable lamp in place to illuminate the gage.

The operation of the device is indicated by the foregoing description in connection 110 with the drawings.

It is essential that no water, steam or

broken glass discharge in the locomotive cab or boiler room because of the fact that most gage glasses are stationed above the fire door, so that breakage of the gage glass would be liable to injure the man doing the firing. By providing discharge pipe 6, a means is afforded for taking steam and water out of range where it will do no damage in case of accident. The arrangement of the gaskets between the shield members and at their ends permit the shields to be adjusted by means of bands 4, 4, and flanged disks 3, 3. In case of breaking of the water tube or for other reasons when it is desired to disassemble the device this may be done by revolving flanged disks 3, 3 and loosening thumb screws 5, 5, which fasten bands 4, 4. The only tool required for the purpose is a small spanner wrench to hook in suitable notches in flanged disks 3, 3 to revolve same.

The foregoing description relates to my shield as applied to a boiler having two gage cocks, as shown in Fig. 1. Where there is only one gage cock in the boiler head and the top connection is made by a tube, a slight difference in flanged disks 3, 3, is necessary, as illustrated in Figs. 7 and 8. A bottom flanged disk 3^a is provided with two ears 19, 19, having perforations 11, 11 for bolts. A similar top flanged disk 3^b has similar ears 19, 19, but differs from disks 3 and from disk 3^a in that it is not provided with screw threads as are the other similar members. Bolts 12, 12 and wing nuts 13, 13 adapted to coact with bolts 12, 12 in operatively connecting disks 3^a and 3^b are provided. Ends of the shield members are made pressure tight by means of bolts 12, 12, which extend through the opposite eared portions of disks

3^a and 3^b and are tightened up by wing nuts 13, 13 as illustrated in the figure showing this modified form of our invention.

What we claim is:

1. In a device of the class described, the combination of a semicylindrical metal shield member having a discharge pipe opening out of its lower portion and having rubber gaskets disposed in grooved longitudinal edges of the said shield member, a corresponding glass shield member, gasket lined adjustable bands fastening the shield members together, opposite lamp bracket members attached to the aforesaid adjustable bands and having horizontally-disposed perforated flange portions, and means connecting the aforesaid flange portions for holding a lamp.

2. In a water gage shield, the combination of a semicylindrical metal shield member having a discharge pipe opening out of it, and provided with gaskets on its longitudinal edges, a corresponding semicylindrical glass shield member, adjustable bands securing the shield members together, lamp-supporting brackets mounted in the aforesaid band members, and means, including gaskets and adjustable disks, for closing the ends of the shield members and effecting gasketed water tight joints at the ends of the shield members, substantially as described.

In testimony whereof we hereunto set our hands in the presence of two witnesses.

JAMES W. LONEY.
THEODORE C. STEGER.
